UNITED STATES PATENT OFFICE.

SILAS W. POULTON, OF HARRISBURG, PENNSYLVANIA.

PICTURE-FRAME.

SPECIFICATION forming part of Letters Patent No. 252,898, dated January 31, 1882.

Application filed May 7, 1881. (No model.)

To all whom it may concern:

Be it known that I, SILAS W. POULTON, of the city of Harrisburg, county of Dauphin, and State of Pennsylvania, have invented Improvements in Picture-Frames; and I do hereby declare the following to be an exact description thereof, reference being had to the accompanying drawings, and to the letters of reference marked thereon, making a part of this specification, in which—

Figure 1 represents a front view of the base A and mat B and panel C, the latter adapted to receive a picture or ornament; Fig. 2, a side view, showing the edge of the base A, the rough-gilded margin of the mat B and the projecting, grooved, and tapering edge of the panel C. Fig. 3 represents a cross-section of the parts A, B, and C, combined on the line *xx* of Fig. 1.

The nature of my invention refers to the construction, arrangement, and combination of a metallic base, A, an ornamented margin with a raised gilded wooden mat, B, inside of the ornamented margin of base A, and a tapering grooved edge panel, C, in front; all being permanently screwed together as a solid panel to be painted upon.

The base A is made of zinc or sheet metal, the surface of which is finished in gold bronze and black figures in lines of any required design or illustration. The base A is the firm and durable border, and on account of its thinness and perfectly-flat character does not warp or crack, and which, when viewed at a distance, has the appearance of being gilded and ornamented upon the wall or place upon which it is hung or fastened, and relieves the picture in front, instead of a finely gilt frame, and is intended as a durable house or car decoration or work of art, the base A extending over the entire back and ornamented on its margin in imitation of a frame.

B is a thin wooden mat with a circular top

and square base, having a rough-gilded margin and fitting upon the center of the metallic base A, the back of which extends over the center surface of the said base A, within the ornamented margin, so as to represent a frame for a center picture in front.

C is the front projecting wooden panel, with its circular top and square base corresponding with the center of the mat B, and fitting upon the mat B inside of the rough-gilded margin of the mat B, the panel C extending over the entire surface of the base of the mat B inside of the raised portion. This front projecting panel, C, has a groove on its outer edge tapering from the front to the rear of the panel, so that the gilded margins of the base A and mat B can be distinctly seen on all sides, giving the requisite relief as a conspicuous frame for a painting in front. This panel C is intended to receive a painting of any kind, or for an engraving, photograph, or other picture.

I am aware that an ornamented single wooden panel with a painting in front is not new. This I do not claim; but

What I claim as my invention, and desire to secure by Letters Patent as new and useful, is—

An ornamental panel composed of the base A, made of sheet metal, gilded and ornamented on the margin in imitation of a picture-frame, with the mat B, having a rough-gilt raised margin within the ornamental margin of the base A and a tapering and grooved edge panel, C, extending over the entire surface of the mat B, within the rough margin of the same, constructed, arranged, and combined as herein described, and for the purpose set forth.

SILAS W. POULTON.
